CLAIM

The ornamental design for a washing machine, as shown and described.

DESCRIPTION

FIG. 1 is a front perspective view of a Washing machine showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 through FIG. 10 are reference views thereof showing the example of the usage of the subject design in consecutive order.

The broken lines in FIGS. 8, 9 and 10 show environmental structure only and form no part of the claimed design.

1 Claim, 10 Drawing Sheets(56)
